METHOD OF CONSTRUCTING FIRE EXTINGUISHERS

Filed July 16, 1928

FIG. 1

FIG. 2

INVENTOR
BY *Charles L. Williams*
E. Lange ATTORNEY

UNITED STATES PATENT OFFICE

CHARLES L. WILLIAMS, OF ALHAMBRA, CALIFORNIA, ASSIGNOR TO FREEMAN GARBEE, OF LOS ANGELES, CALIFORNIA

METHOD OF CONSTRUCTING FIRE EXTINGUISHERS

Application filed July 16, 1928. Serial No. 292,951.

This invention relates to fire extinguishers, of the hand type, and has as one of its objects to provide a non-leakable fire extinguisher which utilizes a liquid fire extinguishing agent and to contain, without leakage, a high air pressure wherewith to forcibly expel the agent.

Another object of the invention is to provide a fire extinguisher that will provide a valve sealed to one end of the extinguisher and communicating with the bottom of the tank, and having a valve seat that is positively sealable to permanently maintain the pressure in the tank.

A further object of the invention is to provide a fire extinguisher in which extinguisher the valve forms a nozzle, the nozzle being adapted to be secured to an air line for charging purposes, having its parts arranged that the influx of air during charging will automatically cleanse the channel from the end of the nozzle through all communicating passages and to the liquid agent.

With these and other objects in view reference is now had to the accompanying drawings in which

Fig. 1 is a side elevation of the device; and

Fig. 2 is a partial sectional elevation of the valve, enlarged.

Having reference to the drawings like numerals refer to like parts throughout the several views and the numeral 1 refers to a storage tank which consists of a seamless tube 2 elongated and having a diameter for convenient handling, and having cast heads 3 threadedly engaging the ends of the tube, as shown in Fig. 1, and further sealed by sweating as in the usual manner by the use of soft solder 4 or the like, and for the purpose of 40 positively preventing any leakage of air due to its high pressure, the pressure being about one-hundred pounds to the square inch.

Contained within this tank is a fire extinguishing agent consisting of carbon-tetra-chloride, a liquid, and which is intended to be directed toward the fire by means of a nozzle 5 and in a manner to be explained.

One of the cast heads is adapted to form the top of the extinguisher and in this head 50 is a valve 6 secured and sealed therein by

threaded engagement and by means of a soft metal washer 7 preferably of lead, being interposed between the valve and the head for sealing purposes.

By this arrangement the valve may be removed for the renewal of the extinguishing agent, the valve then being replaced with a reasonable assurance of perfect sealing by means of the said soft metal washer.

The valve 6 consists of a shell 8 preferably having a raised valve seat 9, as shown in Fig. 2, and a stem 10 is inserted in the shell in threaded engagement with that member and is preferably provided with a hand wheel 11 whereby the valve stem may be raised and lowered to close or open the valve, in the nature of compression cocks, and the valve stem 10 contains a soft metal washer 12 adapted to register with the raised portion 9 of the seat to provide a positive sealable closure for 70 said valve.

A packing nut 13 surrounds the valve stem and engages the shell and contains packing 14 wherewith to maintain that part of the valve perfectly tight, to prevent air leakage 75 at that point during charging.

The valve is further provided with an extended member forming an inner tube 15 which is made a part of said valve, and the inner tube is designed to extend to the bottom of the tank wherewith to provide a passage-way for the extinguishing agent during use.

To provide for filling the tank with air under high pressure and for directing the flow of agent in a direction desired, the nozzle 5 is provided, which nozzle is of the usual type with the exception that it has its outer end 16 threaded for securement to an air line (not shown) whereby the air may enter the tank to supply the pressure necessary to expel its contents.

The nozzle has its inner end 17 positioned adjacent to the metal washer 12 and this, 95 with the inner tube 15 positioned in prolongation of the valve 6, arranges the parts in such a manner that each new charge of air entering the tank will pass through and by these parts to automatically cleanse the pas- 100

sage-way of the liquid of any corroding salts which might have accumulated thereon.

The lead washer 12 used as a valve resists the chemical action of the extinguishing agent and the relatively large inner tube 15, which is preferably constructed of copper, being the only parts which remain in contact with the chemical, thus reasonably provide for a free passage-way of the liquid after 10 an indefinite period of rest, while the small directing channel 18 of the nozzle is not effected by the chemical as it is separated therefrom by the closed valve and permanently cleansed by the entering charge of 15 air.

For the purpose of use the valve is removed from the head in the usual manner, and the tank is filled until about two-thirds full with carbon-tetrachloride.

20 The valve is now replaced and sealed against the lead washer 7 and the nozzle is then threadedly engaged with an air line when the valve is opened by means of the hand wheel and the air pressure is turned on 25 until about one-hundred pounds pressure is forced into the tank.

It is now obvious that this final act of forcing the air back through the valve and into the tank cleanses those parts of any 30 possible obstruction, and that upon closing the valve by means of its hand wheel and against its lead seat that the extinguisher is hermetically sealed until the time of future use.

35 Upon the occurrence of fire, the tank is seized and the valve opened when the air pressure will force the liquid through the nozzle and on to the flames, thus extinguishing the fire.

40 Having thus described my invention, I claim:

1. A method of constructing a fire extinguisher consisting of providing a seamless tube for a container attaching cast seamless 45 heads to the tube, rendering the joints so made airtight by sweating with a solder, providing a threaded aperture in one of said heads, threading a valve for removable and threaded engagement in said aperture and 50 utilizing a soft metal interposed between the valve and head as a sealing means, all for the retention of an extinguishing agent under pressure, providing a nozzle in said valve, and providing a soft metal seat associated 55 with said valve to control the flow of the agent through said nozzle.

2. A method of constructing a fire extinguisher consisting of providing a tube for a container, attaching seamless heads to said 60 tube, rendering the joints so made air tight by sweating with solder, providing a threaded aperture in one of said heads, threading a valve for removal and threaded engagement in said aperture, and utilizing a soft 65 material interposed between the valve and

head as a sealing means, all for the retention of a sealing agent under pressure, providing a nozzle on said valve having its parts arranged for automatic cleansing by the influx of air during charging, and providing a soft metal seat associated with said valve to control the flow of the agent through said nozzle.

In testimony whereof I affix my signature.

CHARLES L. WILLIAMS.
